(57) **CLAIM**

The ornamental design for an abrasive window cleaner pad attachable to a water fed brush, as shown and described.

DESCRIPTION

FIG. 1 is a top, front perspective view of an abrasive window cleaning pad attachable to a water fed brush showing my new design in an assembled state as affixed to the water fed brush;

FIG. 2 is a bottom, rear perspective view thereof, illustrated with the brush partially broken away;

FIG. 3 is a top, front exploded perspective view of the abrasive window cleaning pad attachable to a water fed brush; FIG. 4 is a top, rear exploded perspective view thereof; FIG. 5 is a front elevation view of the abrasive window cleaning pad attachable to a water fed brush from FIG. 1; FIG. 6 is a rear elevation view thereof; FIG. 7 is a left-side elevation view thereof; FIG. 8 is a right-side elevation view thereof; FIG. 9 is a top plan view thereof; and FIG. 10 is a bottom plan view thereof.

The broken lines showing a brush in FIGS. 1 and 2 and three additional abrasive window cleaner pads in FIG. 1 depict environmental matter and form no part of the claimed design. The broken lines seen on the pad itself represent stitching, and are part of the claimed design.
